UNITED STATES PATENT OFFICE.

CLARENCE D. BOTTOMLEY, OF CHARLOTTE, MICHIGAN.

ELECTRIC SWITCH.

Application filed July 8, 1921. Serial No. 483,254.

To all whom it may concern:

Be it known that I, CLARENCE D. BOTTOMLEY, a citizen of the United States, residing at Charlotte, in the county of Eaton and State of Michigan, have invented certain new and useful Improvements in an Electric Switch; and I do hereby declare the following to be a full, clear, and exact description of the invention, such as will enable others skilled in the art to which it appertains to make and use the same.

This invention relates to closing means for electric circuits whereby a single push button when pressed upon closes the circuit against the tension of a spring, the circuit closing elements being retained in closed position by locking means, the latter being automatically released when the button is next pressed upon whereby the circuit is broken.

20 This alternate pressing inward of the push button effects a closing and a breaking of the circuit.

Other objects and advantages will be apparent and suggest themselves as the nature 25 of the invention is understood.

While the drawing illustrates an embodiment of the invention it is to be understood that in adapting the same to meet different conditions and requirements, various changes 30 in the form, proportion and minor details of construction may be resorted to without departing from the nature of the invention.

Referring to the accompanying drawing forming a part of the specification.

35 Figure 1 is a vertical central section of a push button switch embodying the invention showing the parts in normal position.

Figure 2 is a view similar to Figure 1 with the button depressed and the contact 40 elements locked in closed position.

Figure 3 is a view similar to Figure 1 showing the relation of the parts when the button has been depressed a second time to release the circuit closing element.

45 Figure 4 is a top plan view of the switch, the cover and the button being removed.

Figure 5 is a front view of the parts illustrated in Figure 4, and

50 Figure 6 is a detail view.

Corresponding and like parts are referred to in the following description and designated in the several views of the drawing by like reference characters.

The switch comprises a base 1, a cover 2 and a push button 3. The base 1 may be 55 of an insulating material such as compressed

paper, vulcanite or the like. The cover 2 is of dome shape and is adapted to be secured to the base 1 in any preferred way. The block 4 is provided centrally upon the upper or outer side of the base 1 and pivotally supports a member 5 which is normally pressed outwardly at its free end by means of a spring 6 seated in the block 4 and engaging 5 near its pivotal end. The pivoted member 5 preferably consists of a plate which is cut away to provide a cross bar 7. A curved contact 8 is secured to the free end of the pivoted member 5 and is electrically-insulated therefrom. Fixed contacts 9 are secured to the base 1 at opposite sides of the pivoted member 5 and are adapted to engage the curved ends of the contact 8 when the pivoted member 5 is pressed inward. The terminals of the electric circuit 75 are adapted to be connected with the contact 9 in the usual way.

When the free end of the pivoted member 5 is pressed inward and the electric circuit closed by the contacts 8 and 9 engaging the circuit is maintained in closed position by locking means which in the present instance consists of a spring catch 10 secured to the base 1 and extending through a cut away portion of the pivoted member 5 forwardly 80 of the cross bar 7. The spring catch 10 has an inner shoulder 11 which is adapted to engage over the cross bar 7 and hold the free end of the member 5 pressed inward. An outer shoulder 12 of the spring catch 10 is 85 adapted to engage over the forward portion of the pivoted member 5 and limit its outward movement. The spring catch 10 may be of any construction and secured to the base 1 in any convenient and substantial 90 way.

The button 3 is mounted in a boss of the cover 2 and is free to move in and out but is held from rotating by a pin and slot connection. The pin 13 is carried by the 100 button 3 and the slot 14 is formed in a side of the boss of the cover 2 in which the button 3 is mounted. The outer end of the slot 14 is closed to limit the outward movement of the button. An expansible helical spring 15 normally exerts a pressure to hold the button 3 pressed outwardly. The spring 15 is mounted upon an extension 16 of the button which forms a guide therefor. The inner end of the spring 15 is seated in 110 an opening formed in the block 4. A trip 17 is pivoted within a groove 18 formed in

a side of the button 3 and its free end is formed with a shoulder 19 and a bevel 20. A spring 21 normally exerts a lateral pressure on the trip 17 to move its free end outwardly to coat with the spring catch 10 and the pivoted member 5. The spring 21 is seated in a recess formed in a side of the button 3.

When the parts comprising the switch are properly assembled they appear substantially as illustrated in Figure 1 when in normal position. To close the switch the button 3 is pressed inward as indicated in Figure 2. The extremity of the trip 17 engages the cross bar 7 of the pivoted member 5 and when the button 3 is pressed inward to the limit of its movement the cross bar 7 clears the inner shoulder 11 of the catch 10, and the latter swings inward to cause the shoulder 11 to engage over the cross bar 7 and lock the pivoted member 5 and hold the switch in closed position. This is indicated most clearly in Figure 2. Upon releasing the button 3 the same moves outward under the action of the spring 15. To break the circuit it is necessary to move the button 3 inward a second time. This causes the beveled end 20 to ride upon the spring catch 10 and disengage the shoulder 11 thereof from the pivoted member 5, the shoulder 19 of the trip 17 engages a second shoulder 12 of the catch 10 thereby limiting the inward movement of the button 3 and holding the catch 10 clear of the pivoted member so that upon releasing the button 3 both it and the pivoted member 5 move outward, thereby breaking the circuit by the separation of the contacts 8 and 9. This operation is indicated most clearly in Figure 3 which illustrates the button 3 at the limit of its inward movement and the catch 10 clear of the pivoted member 5. The inward movement of the button 3 upon the release stroke is less than the inward movement to effect closing of the switch this being due to the engagement of the shoulder 19 with the shoulder 21.

Having thus described the invention, what I claim is:—

1. An electric circuit closer of the character specified, comprising a relatively fixed

contact, a movable member provided with a cooperating contact, a catch, a push button for depressing the movable member, and a movable trip carried by the push button and adapted to engage both the catch to move it laterally and the said movable member to press the same inwardly. 55

2. An electric circuit closer of the character specified, comprising a relatively fixed contact, a movable member provided with a cooperating contact, a catch having a lateral shoulder to engage the movable member, a push button, and a movable trip carried by the push button and having a shoulder to engage the shoulder of the catch. 60 65

3. An electric circuit closer of the character specified comprising a relatively fixed contact, a movable member provided with a cooperating contact, a catch having opposed shoulders at different points in its length, a push button, and a movable trip carried by the push button and adapted to engage and coat with the shoulders of the catch. 70

4. An electric circuit closer of the character specified comprising fixed contacts, a pivoted member, a contact carried by the pivoted member and electrically insulated therefrom and adapted to cooperate with the fixed contact, a spring catch extending through the pivoted member and having inner and outer shoulders, a push button, and a pivoted trip carried by the push button and having a shoulder at its inner end. 75 80

5. A circuit closer comprising a spaced fixed contact thereon, a pivoted member, a cooperating contact carried by the pivoted member and electrically insulated therefrom, a cover, a push button mounted in the cover and held from turning and a trip pivoted to the push button and adapted to effect release of the pivoted member at each alternate inward movement of the push button. 85 90 95

In testimony whereof I affix my signature in presence of two witnesses.

CLARENCE D. BOTTOMLEY.
